OTHER PUBLICATIONS

Fifteen pages of photographs for Vocollect Model AH-10 Headset sold as early as 2007.

Primary Examiner — Cathron Brooks

Assistant Examiner — Katie Mroczka

(74) Attorney, Agent, or Firm — Wood, Herron & Evans, LLP

(57) **CLAIM**

The ornamental design for a microphone, as shown and described.

DESCRIPTION

FIG. 1 is a front perspective view of the microphone;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top view thereof; and,

FIG. 8 is a bottom view thereof.

The broken line elements illustrated in the Drawing Figures are for the purpose of illustrating the environment of the invention and form no part of the claimed design.

1 Claim, 4 Drawing Sheets
